UNITED STATES PATENT OFFICE

WILLIAM A. GAMMACK AND DONALD G. KNOX, OF LONG BEACH, CALIFORNIA, ASSIGNEES, BY MESNE ASSIGNMENTS, TO JORDON & TAYLOR, INC. OF LOS ANGELES, CALIFORNIA, A CORPORATION OF CALIFORNIA

PERIODIC CIRCUIT MAKER

Original application filed July 5, 1928, Serial No. 290,410. Divided and this application filed July 11, 1937. Serial No. 204,939.

Our invention relates to a periodic circuit maker for use in connection with oil well pumping apparatus, as is fully covered in our copending application Serial Number 5 290,410, filed July 5, 1928. This application is a division of our application above referred to.

It is an object of our invention to provide a periodic circuit maker so constructed that 10 the duration of time during which any one of the contacts is energized may be varied without varying or changing the duration of time during which the other contacts are energized.

15 It is a further object of our invention to arrange the driving means so that the distributor is rotated at different peripheral velocities during different portions of the distributing cycle.

20 It is a further object of our invention to so arrange the distributor driving means that during different predetermined portions of the distributing cycle the driving means rotate the distributor at different predetermined peripheral velocities.

25 It is a further object of our invention to provide means in a periodic circuit maker for simultaneously varying the speed of the driving means with each selected portion of 30 the distributing cycle.

Other objects and advantages, uses and characteristics of our invention will become apparent from the subsequent detailed discussion and description of our invention and 35 one preferred form thereof. In describing our invention, reference will be had to the attached drawings in which:

Fig. 1 is a side elevational view of the intermittent switch of our invention.

40 Fig. 2 is a top view of the intermittent switch.

Fig. 3 is a sectional view taken along the line 4—4 of Fig. 2.

Fig. 4 is a vertical sectional view through 45 the distributor of the invention taken along the line 5—5 of Fig. 2.

Fig. 5 is a partially sectioned view showing the governor of the intermittent switch.

Fig. 6 is a horizontal sectional view taken 50 along the line 7—7 of Fig. 1.

Fig. 7 diagrammatically shows the means of varying the speed of the intermittent switch.

Figs. 1 to 7 inclusive show the intermittent switch 15 of the invention. This switch comprises a motor 16 which is supported on feet 17 and which has a frame-work 19 supporting a top plate 20. Vertically pivoted in the top plate 20 and supported at its lower end by a jewel bearing 22 is a vertical shaft 24 of the motor 16 which carries near its central portion a disc 25 secured thereto by a set screw 26. Between the disc 25 and the top plate 20 is a pair of laminated cores 27 carrying windings 28. Directly below each of the laminated cores 27 is a laminated core 30 carrying a winding 31. The windings 28 and 31 are suitably connected to a source of alternating current, and set up eddy currents in the disc 25, which is supported between the cores 27 and 31, thus causing it to rotate about its vertical axis. This is a well known type of induction-disc-motor such as is found in certain types of watt-hour meters and in certain electrically driven phonographs. The rate of rotation of the rotor of the motor is controlled by a governor which will now be described.

Mounted on the shaft 24 below the disc 25 is a helical gear 35 which meshes with a worm 36 cut in a horizontal shaft 38 pivotally supported by bearings 39 and 40, as best shown in Fig. 5. Adapted to slide on the horizontal shaft 38 is a sleeve 42 which has a friction plate 43 and a hub 44 at its left end. A similar hub 46 is formed integral with the right end of the horizontal shaft 38. Connecting the hubs 44 and 46 are flat springs 48, three in number, each supporting at its central point a weight 50. The weights 50 fly outward as the speed of the horizontal shaft 38 is increased, and thus pull the friction plate 43 to the right.

Adapted to frictionally engage the friction plate 43 on its right-hand face, as shown in Fig. 5, is a brake 54 mounted on an arm 56 which arm is pivotally supported in the frame 19 by a bolt 58. As the brake 54 is moved to the right, pivoting about the bolt 58, the tendency of the disc 25 is to rotate

faster, its load being partially removed, thus allowing the weights 50 to move outward until they draw the friction plate 43 into engagement with the brake 54, at which time 5 the speed of the disc 25 will be held constant.

The upper end of the vertical shaft 24 carries a worm 60 which engages a worm gear 61 mounted on a horizontal shaft 62 which rotates a distance above the top plate 20 in 10 brackets 64 and 65 as most clearly shown in Fig. 3. An annular groove 66 is cut in the top plate 20 to allow clearance for the worm gear 61 to rotate, this rotation being transferred to the horizontal shaft 62 by means of 15 a set screw 68. The left end of the horizontal shaft 62 carries a worm 70 which is meshed with a helical pinion 72 carried on a counter-turned portion 73 of a vertical shaft 74, as shown in Fig. 4.

20 This vertical shaft 74 passes centrally through a distributor 75 of the invention. The distributor 75 is secured to the top plate 20 by screws 76 passing through a housing 77 made of suitable insulating material. 25 Screwed into the bottom of the housing 77 and surrounding the vertical shaft 74 is a bearing 79 provided with a stuffing box 80. The stuffing box 80 forms a liquid-tight seal between the housing 77 and the vertical 30 shaft 74.

Equally spaced around the shaft 74 are downward projecting sleeves 82 each holding a contact sleeve 83 which in turn is engaged by, and electrically connected with, a plug 84. 35 Each plug 84 is connected by a wire through a cable 85 with one of a series of six binding posts 87 which are mounted in a piece of insulating material 88 forming a part of the top plate 20, as shown best in Figs. 1 and 2. The 40 counter-turned portion 73 of the vertical shaft 74 extends through a cup portion 90 of the housing 77, and carries a rotor 91 which has an insulating sleeve 92, as shown in Fig. 4. Surrounding the insulating sleeve 92 is a 45 metallic sleeve 93 which carries a rotor-contact 95. This rotor-contact 95 rotates with the shaft 74, and in so rotating comes consecutively into contact with a series of six 50 stationary contact arms 97, each of which is mounted on the upper end of one of the contact sleeves 83.

The rotor-contact 95 remains in contact with each of the contact arms 97 for one-sixth of a revolution of the vertical shaft and immediately on sliding past one contact arm immediately springs outward into contact with the succeeding contact arm. As the spring contact moves over this new contact arm its free end follows the contour of the 60 arm and is pushed inward. Reaching the edge of this contact arm the free end of the spring contact quickly flies outward, breaking contact with the contact arm previously guiding it inward and making contact with 65 the succeeding arm. This operation is con-

tinued throughout each revolution of the vertical shaft 74.

A brush 98 is adapted to bear against the upper end of the metallic sleeve 93, being secured to the insulated housing 77 by means of a terminal 99, as indicated best in Fig. 2. The cup portion 90 of the housing 77 may be filled with oil to a level indicated at 100. This oil will effectively stop any sparking that may occur as the spring contact 95 breaks 75 contact with one of the contact arms 97.

Mounted on the lower end of the vertical shaft 74 is a collar 102 which supports six equally spaced screws 104 which are threaded radially inward toward the center of the shaft 74. The distance between the axis of the shaft 74 and a head 105 of each screw 104 can be varied by turning the screw 104. These screws are locked in place when completely adjusted by means of lock nuts 106 which screw onto the screws 104 and bear against the outer periphery of the sleeve 102. 80

The heads 105 of the screws 104 are adapted to consecutively engage a curved plate 107. The curved plate 107 has a foot 108 carrying a groove 109. Extending through the groove 109 and threaded into the arm 56 are two screws 110 for the purpose of clamping the curved plate 107 and the arm 56. By loosening the screws 110 the curved plate 107 may 85 be moved in a direction parallel to the grooves 109, as shown in Fig. 7, for a purpose to be described later. A spring 112 is secured to the arm 56 and also to a point on the frame 19 and is for the purpose of holding the screw 100 heads 105 of the screws 104 against the curved plate 107.

When the motor 16 is energized the rotation of the disc 25 is transferred to the vertical shaft 74 through the reduction gears 113 previously described. As the shaft 74 rotates it carries with it the sleeve 102 and the screws 104 held therein. As the screws 104 rotate about the axis of the shaft 74 they consecutively contact the curved plate 107, causing the arm 56 to slowly oscillate about the pivot 58. Referring to Fig. 7, the maximum counter-clockwise oscillating movement of the arm 56 caused by one of the screws 104, is shown in full lines and occurs when one of the 115 screw heads touches the curved plate at a point that is on the line of centers of the shaft 74 and the center of curvature of the curved plate 107. As the shaft 40 is rotated in the direction of the arrow 115 the arm 56 rotates slightly in a clockwise direction, until a point is reached where two screw heads 104 are simultaneously contacting the curved plate 107. As the shaft 74 rotates still further the next screw head determines the movement of the arm 56. If this screw head is at a distance from the axis of the shaft 74 a distance less than that of the preceding screw head, the arm 56 will reach its maximum counter-clockwise swing, as indicated by the dotted 120

lines 117 of Fig. 8, at the time that the screw head touches the line of centers between the axis of the shaft 74 and the center of curvature of the curved plate 107. This oscillating 5 of the arm 56 around the point 58 causes the brake 54 to change its position relative to the frame of the machine and thus allows the friction plate 43 of the governor to slowly oscillate in step with the oscillations of the arm 56. As the friction plate 43 thus moves side 10 to side the speed of the motor 16 is consequently increased or diminished as the case may be in step with the oscillations of the arm 56.

It should be clear that even if all the screw 15 heads 105 were to be the same distance from the axis of rotation of the shaft 74 the arm 56 would still oscillate and the speed of the motor would still vary in step with these oscillations. When one of the screws 104 is 20 screwed further into the sleeve 102 the average speed of the motor during the time this screw is in engagement with the curved plate 107 is slower than the average speed during the engagement of the other screws. Thus 25 the length of time that a circuit is closed between the terminal 99 and any one of the binding posts 87 can be regulated by varying the distance between the screw head 105 in use with that particular contact and the axis 30 of rotation of the shaft 74. Or, if the whole series of times of contact is to be lengthened or shortened simultaneously the screws 110 are loosened and the curved plate 107 moved respectively toward or away from the axis of 35 rotation of the shaft 74.

The timing between the distributor and the speed control mechanism can be varied by slightly rotating the sleeve 102 with respect to the shaft 74, but we prefer to so time the 40 two that the circuit in the distributor is broken at the instant of maximum clockwise rotation of the arm 56; in other words, at the time the two screw heads 105 are in contact with the arm 56 simultaneously.

45 The intermittent switch 15 is valuable not only in the capacity shown but may be used in numerous other installations such as sign lighting or in other circuits requiring intermittent control.

50 The application of this intermittent switch to a series of wells already on production does not require the building of a single compressor plant to supply all of the wells. Instead, the compressors of each well, already 55 in use, may be connected together. Our invention is not limited to the use of a unitary compressor plant. It is advantageous, however, to use such a unitary compressor plant, locating all of the main valves, the relief 60 valve, and the pop valve in the compressor plant itself. The intermittent switch 15 should also be located inside the plant, thus bringing the whole operating mechanism within the control of a single operator. We 65 have found it advantageous to use a record-

ing pressure gauge 230 connecting to the header 131, thus recording at all times the pressures supplied to the different wells. It is also advantageous to insert a pilot light in each of the wires leading from the binding posts 87 to the solenoids 136. These pilot lights will be lighted during the time that current is passing to the solenoid winding, and consequently during the time that the main valve to that well is open, indicating 75 to the operator that the well is being charged.

We claim as our invention:

1. In a switch, the combination of: a distributor carrying contacts; contacting means for successively contacting said contacts, said means breaking contact with one of said contacts and instantaneously making contact with the next of said contacts; and means for simultaneously varying the time of contact between said contacting means and each 80 of said contacts.

2. In a switch, the combination of: a distributor carrying contacts; contacting means for successively contacting said contacts, said means breaking contact with one of said contacts and instantaneously making contact with the next of said contacts; and means for individually varying the time of contact between said contacting means and each of said 85 contacts.

3. In a switch, the combination of: a distributor carrying contacts; contacting means for successively contacting said contacts, said means breaking contact with one of said contacts and instantaneously making contact with the next of said contacts; and means for individually and simultaneously varying the time of contact between said contacting means and each of said contacts.

4. In a switch, the combination of: a distributor carrying contact arms; a rotating means for successively completing a circuit between said contact arms and said rotating means, said rotating means breaking one of 100 said circuits and instantaneously making the 105 succeeding of said circuits; and means for individually varying the time each of said circuits is completed.

5. In combination: a distributor having stationary and movable contacts; a drive 110 means for said distributor; a governor regulating the speed of said drive-means; an arm adapted to control said governor; and engaging means carried by said distributor 115 for engaging said arm, thereby regulating the speed of said drive-means, said engaging means being adjustable to vary the time said stationary and said movable contacts are in engagement.

6. In combination: a distributor having a series of contact arms; a rotor carrying a 120 rotor-contact adapted to engage said contact arms; a shaft through said rotor; a spider carried by said shaft and having arms; a motor adapted to drive said distributor; and 125

an arm bearing against said spider arms, the position of said arm controlling the speed of said motor, said arms of said spider being so adjustable as to vary the time of contact between said rotor-contact and each of said stationary contacts.

7. In a timer, the combination of a distributor head comprising a body, contacts positioned in said body, a drive shaft rotatably mounted in said body, a rotor carried by said shaft, a brush carried by said rotor and arranged to successively contact said contacts, means for making an electrical connection to said rotor brush; means for driving said distributor head shaft comprising a motor means, and power transmitting means operatively connecting said motor with said distributor head shaft; means for controlling the speed of said driving means for each successive contact comprising a governor driven by said driving means and carrying a brake disc, an adjustable brake mechanism arranged to engage said brake disc, and means carried by said distributor head shaft for operating said adjustable brake mechanism, said last named means including a separate independently adjustable means for adjusting the distributor speed for each respective contact.

8. In a timer, the combination of a distributor head comprising an oil-tight body, contactors positioned in said body and arranged to be submerged in oil, a drive shaft rotatably mounted in said body, a stuffing box carried by said body through which said shaft passes so as to maintain said body oil tight, a rotor carried by said shaft, a brush carried by said rotor and arranged to contact said contactors, means for making an electrical connection to said rotor brush; driving means for said distributor comprising a motor means, and power transmitting means operatively connecting said motor with said distributor shaft; means for controlling the speed of said driving means for each successive contactor comprising a centrifugal governor, driven by said driving means and carrying a brake disc, an adjustable brake mechanism arranged to engage said brake disc, and means carried by said distributor head shaft for successively operating said brake mechanism, said last named means including a separate independently adjustable means for adjusting the distributor speed for each respective contactor.

9. In combination, a distributor having movable contact means and relatively stationary contact means cooperating therewith, driving means for moving said movable contact means through a cycle of operations including engagement of the contact means and disengagement thereof, and means driven by said driving means for variably controlling the speed of said driving means during different portions of the cycle.

10. In combination, a distributor having movable contact means and relatively stationary contact means cooperating therewith, driving means for moving said movable contact means through a cycle of operations including engagement of the contact means and disengagement thereof, means driven by said driving means for causing said driving means to operate at one predetermined speed during one portion of the cycle and at another predetermined speed during other portions of said cycle, and means for adjustably varying said predetermined speeds.

11. In combination, a distributor having movable contact means and a plurality of stationary contact means cooperating therewith, driving means for moving said movable contact means through a cycle of operations including successive contact with said stationary contact means, and means driven by said driving means for causing said driving means to operate at different predetermined speeds during different portions of said cycle.

12. In combination, a distributor having movable contact means and a plurality of stationary contact means cooperating therewith, driving means for moving said movable contact means through a cycle of operations including successive contact with said stationary contact means, and means driven by said driving means in synchronism with said movable contact means for varying the speed of said driving means during different portions of said cycle.

13. In combination, a distributor having movable contact means and a plurality of stationary contact means cooperating therewith, driving means for moving said movable contact means through a cycle of operations including successive contact with said stationary contact means, and means driven by said driving means for causing said driving means to operate at different selected speeds during contact with each of said stationary contact means.

14. In combination, a distributor having movable contact means and relatively stationary contact means cooperating therewith, driving means for moving said movable contact means through a cycle of operations including engagement of the contact means and disengagement thereof, a governor for limiting the speed of said driving means, and means driven by said driving means for variably adjusting said governor during different portions of said cycle to thereby cause said driving means to operate at different selected speeds during different portions of said cycle.

In testimony whereof, we have hereunto set our hands at Torrance, California, this 20th day of June, 1927.

WILLIAM A. GAMMACK.
DONALD G. KNOX.
